(57) **CLAIM**

The ornamental design for a bubble diverter, as shown and described.

DESCRIPTION

FIG. 1 is a perspective view of our bubble diverter;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof;

FIG. 8 is another front view of our bubble diverter showing additional environmental features; and,

FIG. 9 is a perspective view thereof.

The broken line portions of the disclosure are included for the purpose of illustrating environment and form no part of the claimed design.

1 Claim, 8 Drawing Sheets
